UNITED STATES PATENT OFFICE.

CARL VALDEMAR BIRK, OF BORUP, DENMARK.

HORSE-POWER.

SPECIFICATION forming part of Letters Patent No. 399,478, dated March 12, 1889.

Application filed November 1, 1888. Serial No. 289,717. (No model.) Patented in England September 24, 1888, No. 13,777; in France December 3, 1888, No. 193,680, and in Germany January 14, 1889, No. 46,642.

To all whom it may concern:

Be it known that I, CARL VALDEMAR BIRK, a subject of the King of Denmark, residing at Borup, Kingdom of Denmark, have invented 5 certain new and useful Improvements in Horse-Powers, (for which Letters Patent here-
tofore were granted to me by the governments
of England, dated September 24, 1888, No.
13,777; France, dated December 3, 1888, No.
193,680, and Germany, dated January 14, 1889,
No. 46,642;) and I do declare the following to
be a full, clear, and exact description of the
invention, such as will enable others skilled
in the art to which it appertains to make and
use the same.

This invention relates to improvements in
that class of devices known as "horse-powers,"
and which are provided for the purpose of
utilizing the power of a horse for driving ma-
chinery and other similar purposes; and the
object of my invention is to provide a horse-
power in which few gear-wheels are used for
giving the driven wheel a great speed of rota-
tion, and which also reduces the friction, and
is so constructed that the sudden jolts pro-
duced by the irregular movements of the horse
do not affect the driven machinery.

The invention consists in the combination,
with an upright spindle, of a frame mounted
30 to rotate horizontally on the same, shafts in
said frame, a wheel fixed on the outer end of
each shaft and running on a suitable track, a
cog-wheel connected with the inner end of each
shaft, and a cog-wheel driven by the cog-
wheel on the inner ends of the shafts.

The invention also consists in the construc-
tion and combination of parts and details, as
will be fully described and set forth herein-
after, and pointed out in the claims.

40 In the accompanying drawings, Figure 1 is
a central longitudinal vertical sectional view
of my improved horse-power, parts being
broken out. Fig. 2 is a plan view of the same,
parts being broken out.

45 Similar letters of reference indicate corre-
sponding parts.

The spindle A is secured in a suitable base,
K, and on the upper end of said spindle a
sleeve, L, is mounted to rotate, on which is
50 fastened a transverse piece, T.

From each end of the transverse piece T
two beams, B, are secured, and are inclined
toward each other in horizontal plane, their
outer ends being secured to a bearing, F. In
said bearing F a shaft, A', is journaled, on the 55
outer end of which a wheel, E, is rigidly
mounted. The inner ends of the shafts A are
connected by universal joints S with two op-
posite beveled cog-wheels, H' H², mounted
loosely on the common bolt or pin m, passed 60
transversely through the piece T. Said bevel-
ed cog-wheels H' H² engage a beveled cog-
wheel, D, made integral with a sleeve, M,
mounted loosely on the spindle A, said sleeve 65
M being connected with the beveled cog-wheel C',
also mounted loosely on the spindle A, and
engaging the beveled cog-wheel C², mounted
on the horizontal shaft C¹, connected by a uni-
versal joint with the power-transmitting shaft
C³. In place of using the cog-wheels C' C², 70
belts and pulleys or other devices may be used
for transmitting motion from the sleeve M.

The wheels E run on the circular track C,
but may be arranged to run on any other suit-
able support. A horse is connected with the 75
frame formed by the beams T and B at one or
both bearings, F. The horses are driven around
in a circle, and the wheels E revolve and ro-
tate the beveled cog-wheels described. The
shafts A' are connected with the cog-wheels 80
by universal joints for the purpose of avoid-
ing undue bending and twisting strains.
When the horses draw suddenly, the wheels E
slide on their track, and thus no jolts or jars
are transmitted to the gear-wheels H', H², and 85
D. By properly weighting the frame B, or in-
creasing the weight of the wheel E, the fric-
tion between the wheels and the track can be
increased, and thus more power obtained.

Having thus described my invention, I claim 90
as new and desire to secure by Letters Patent—

1. In a horse-power, the combination, with
a spindle, of a sleeve on the same, a cross-bar
on said sleeve, beams secured to the ends of
said cross-bar and inclined toward each other, 95
bearings secured to the outer meeting ends of
said beam, shafts journaled in said bearings,
and wheels secured on the outer ends of the
shaft and running on a suitable support, cog-
wheels connected with the inner ends of the 100

shafts, and a cog-wheel mounted loosely on the spindle and engaged with the cog-wheels on the inner ends of the shafts, substantially as set forth.

- 5 2. In a horse-power, the combination, with an upright spindle, A, of the sleeve L on the same, the cross-piece T on the sleeve L, beams B, secured to the cross-piece C and to bearings F, the shafts A', journaled in the bearings F, wheels E, fixed on the outer ends of the shafts A, the beveled cog-wheels II' II², connected
- 10

with the inner ends of the shafts A', the transverse bolt m in the cross-bar T, on which bolt m the wheels H' H² are mounted, and the cog-wheel D, loosely mounted on the spindle A, 15 substantially as set forth.

In testimony whereof I have affixed my signature in presence of two witnesses.

CARL VALDEMAR BIRK.
